CENTRIFUGAL HAND MISSILE LAUNCHER

Harlow B. Grow, Linden, Mo.

Application February 27, 1948, Serial No. 11,375

9 Claims. (Cl. 46—81)

1

This invention relates generally to launchable missiles and launching means for such missiles, and is particularly applicable to toys, such as model airplanes, and launching devices for the latter.

One of the objects of the present invention is the provision of a launchable missile in combination with launching means for such missile, and wherein said launching means comprises a rotary member journaled in a fixed handle, the latter having means for arresting the movement of the rotary member at will, and with which rotary member is secured a rotatable missile-engaging element so arranged as to release the missile when the movement of the rotary member is momentarily stopped.

Another object of this invention is to provide a missile in the shape of a toy, such as a model airplane, provided with an engageable element, and a launching device including a handle and a rotary member journaled in the handle, and with which rotary member is associated, by means of two flexible connectors, a substantially hook-shaped, rotatable missile-engaging element adapted for engagement with the engageable element of the missile, and wherein the handle is provided with hand-operable means for stopping the rotation of said rotary member whereby the two connectors between the rotary member and the hook-shaped element are caused to change their position so that the hook-shaped element is rotated to release the missile and launch it.

Still another object of this invention resides in the provision of a launcher for missiles of the type indicated, and which missile launcher is equipped with stop means for arresting the movement of the rotary part of the launcher at will, and wherein position indicating means for said stop means are provided whereby the desired type of launching a missile is determined.

The foregoing and still further objects and important advantages of the present invention will become more fully apparent from the following description in connection with the accompanying drawings, forming illustrative parts of the present invention, but intended to serve merely for descriptive purposes without confining this invention to the specific showing, and wherein:

Fig. 1 is a perspective illustration of the device in accordance with the present invention;

Fig. 2 is a section taken on line 2—2 of the upper part of Fig. 1;

Fig. 3 is a partial sectional view through the rotary member of the device, taken on line 3—3 of Fig. 1;

2

Fig. 4 is a vertical section through the hook-shaped element of the device;

Fig. 5 is a partial section made through the missile along line 5—5 of the lower part of Fig. 1;

Fig. 6 is a section taken on line 6—6 through Fig. 5;

Fig. 7 is a diagrammatical illustration, partly in section along line 7—7 of Fig. 1, of the device, with its rotary parts shown in full lines preparatory to the point of launching the missile, and with the rotary parts being shown in broken lines at the point the missile is being released, the device being viewed in the direction of the section line arrows 7—7;

Fig. 8 is a diagram of the device shown at a point of launching the missile in another manner than that indicated in Fig. 7, and the view taken being in the direction of the arrows of section line 7—7 of Fig. 1; and

Fig. 9 illustrates a modified construction of the launcher, partly in cross section.

Referring now specifically to the figures, numeral 10 denotes a hollow handle provided with a disc-like flange 11, at the periphery of which latter are indicated differently colored areas, such as red, green and blue, enumerated, respectively, at 12, 13 and 14. In a suitable enlargement 15 of disc 11 there is mounted a spring-loaded plunger 16, the purpose of which will be explained presently.

Operatively associated with handle 10 is a rotary member 17 composed of a shaft 18 journaled in the hollow part of the handle, and with which shaft is fixedly associated a T-shaped member 19 composed of arms 20 and 21. Arm 21 has a wedge-shaped extension 22, projecting toward flange 11, and being adapted for engagement by plunger 16 when the latter is thrust from its full-line position shown in Fig. 2 to its broken-line position. It will be noted that when plunger 16 is in its full line position, wedge-shaped extension 22 will clear it (see Fig. 3); obviously arm 20 must always clear plunger 16.

Secured to arms 20 and 21, by means of flexible connectors 23 and 24, is a missile-engaging element 25 comprising a substantially hook-shaped, ring formation having an outer peripheral channel or groove in which flexible connectors 23 and 24 are movably guided, as clearly seen in Fig. 4.

The ends of these connectors are secured to the respective ends 26 and 27 of element 25.

A missile intended to be launched by the above described device is preferably in the form of a flying toy, such as a model airplane 28, and is provided with a recess 29. Transversing the recess is an engageable element in the shape of

a pin 30, adapted to be engaged by missile-engaging element 25 in the manner shown in Fig. 1, recess 29 serving to not only accommodate the element 25 but to permit it to rotate, and to guide it while being rotated to a missile-releasing position.

Modification

Fig. 9 discloses a different construction of the missile launcher, although its function in respect to the missile remains unaltered. The handle 31 of the launcher is split longitudinally, its two halves being united along plane 32 when all its parts are assembled.

A journal 33 for a relatively short shaft 34 is centrally located in the handle and is provided with a suitable end recess for accommodating an annular shaft enlargement 35. That enlargement limits the longitudinal movement of the shaft in its journal.

Attached to the shaft end projecting from the handle is a double bar 36 provided with end perforations for accommodating the ends of flexible connectors 23 and 24 extending to missile-engaging element 25, as in Fig. 4.

Arranged about midway between the outer shaft end and enlargement 35 there extends from the shaft a pin 37 which is free to revolve in a suitable recess. Movable mounted in the upper half of the handle is a plunger 38, normally urged in outward direction by a spring 39, and having an interior enlargement for limiting its outward movement. An extension 40 of the plunger is intended to engage pin 37 when it is desired to arrest the rotation of the shaft.

At the periphery of the handle there are provided markings in different colors, such as red, green and blue numbered, respectively, at 12, 13 and 14. These markings facilitate the positioning of the handle at three different angles to the normal, whereby three different types of the launching of the missile are effected, as has been explained in connection with Fig. 1.

Operation

When it is desired to launch the missile, the latter is suspended from the launcher by means of hook-shaped element 25, in the manner illustrated in Fig. 1. The launcher handle is then swung until rotary member 17 commences to revolve within the handle in such a way that the front face of wedge-shaped extension 22 moves in the direction toward stop plunger 16. Such direction would be counter-clockwise when observing Fig. 1, and clockwise when observing Figs. 7 and 8.

When the missile has attained the desired velocity, plunger 16 is thrust into the path of wedge-shaped extension 22, in the manner indicated in Fig. 7. As a result, rotor 17 is stopped, while missile 28, still engaged by hook-shaped element 25, continues in its travel. Due to the now fixed position of the rotor, connectors 23 and 24 change their position, and, due to their positional change, commence to revolve missile-engaging element 25 in a plane passing through the peripheral groove thereof. During this positional change of the connectors, connector 23 so-to-speak unwinds itself from element 25, whereas a portion of connector 24 is wound up on that element, in the manner indicated in broken lines in Fig. 7. This revolving movement of element 25 causes the latter to release pin 30 of missile 28, thereby launching the missile.

As stated in connection with the description of Fig. 1, handle flange 11 is equipped with red,

green and blue markings at its periphery. When it is desired, for instance, to so launch the model airplane that it attains a high altitude, handle 10 is held with the red marking of flange 11 top-most, while the airplane is suspended from the hook in the manner shown in Fig. 1. When now stop plunger 16 is thrust into the path of wedge extension 22, airplane 28 is released while it travels upwards, as indicated in broken lines in Fig. 7.

When it is desired to launch the model airplane for a great distance flight, instead of for attaining a high altitude, the launching must take place a moment earlier than is required for a high altitude launching. In other words, stop plunger 16 is thrust into the path of wedge extension 22 when blue field 14 of flange 11 is uppermost. Great distance launching is indicated in Fig. 8. When a medium flight is desired ranging between high altitude and long distance, the handle must be held with green field 13 of flange 11 in the uppermost position.

In all events handle 10 is held parallel to the ground and the plane is released when hook 25 is below the handle.

From the above described launching operations it becomes clear that the operator of the device is completely relieved from the necessity of exercising particular skill to determine the point of release for any desired flight of the missile, the only requirement being that the operator holds the handle with the color designating the desired flight in uppermost position.

It is to be understood that the launching operations described in conjunction with the embodiment disclosed in Fig. 1 apply equally to the launcher modification illustrated in Fig. 9.

While in the foregoing specific structures of the present device are described, it is quite obvious that changes and improvements may become necessary in adapting the device for launching different types of missiles, such changes and improvements lying within the broad scope of the present invention as defined in the annexed claims:

I claim:

1. In a toy, a launcher for a missile, said launcher comprising a handle, a rotary member journaled in the handle, a hook-shaped, movable element for releasably engaging the missile, a pair of connectors attached with one of their respective ends to said rotary member, their other ends being associated with the ends of said element so that the latter is held in a missile-engaging position, and manually operable means operative in said handle and adapted to be moved into the path of said rotary member for arresting the movement of the latter, thereby effecting a positional shift of said connectors, thus causing said element to move to its missile-releasing position, and a missile releasably suspended from said element.

2. In a toy, a missile launcher comprising a handle, a rotary member journaled in and partly extending from the handle, arms provided at the extending portion of the rotary member, a hook-shaped rotatable missile-engaging member, a pair of spaced connectors secured with one of their ends to the arms of the rotary member, the other connector ends being attached to the ends of the missile-engaging member, a missile having means for engagement by and being suspended from said latter member; spring-loaded, hand-operable stop means for the rotary member operatively mounted with said handle and being

adapted to be momentarily placed into the path of rotation and to arrest the movement of the rotary member for the purpose of turning, by way of said connectors, said missile-engaging member, for releasing said missile.

3. In a toy as per claim 2, said handle having peripheral means for indicating desired positions of said stop means, whereby the type of launching of the missile is determined.

4. The combination with a launchable missile, of a launching device comprising a handle, a rotor composed of a shaft journaled in and partly extending from the handle, a bar affixed to the extending portion of the shaft, a substantially hook-shaped element for releasably engaging a missile, a missile suspended from said element, a pair of connectors extending from said bar to said element, said handle having a flange, a spring-loaded stop member operatively mounted in said flange and being adapted, when operated, to project into the path of rotation and to arrest the rotation of said bar, thereby so changing the position of said connectors in respect to said element that the latter is moved to its missile-releasing position at which the missile is launched.

5. The combination with a toy airplane, of a launching device for the latter, said launching device comprising a hollow handle having a circular flange at one end, a rotor journaled in the handle and comprising a shaft and a bar secured to the shaft, said bar having a wedge-shaped extension projecting toward said flange, a manually operative stop member mounted in the flange, a spring normally urging said stop member away from said bar extension, an engaging element for the toy airplane movably connected by flexible members with said bar and comprising a substantially hook-shaped formation with a grooved outer periphery for the accommodation of said flexible members, said stop member being adapted, when manually operated, to move into the path of said bar extension and to stop the rotation of the bar, whereby the flexible members are caused to turn said airplane-engaging element to its airplane-releasing position for launching said airplane, and indicating means provided at the periphery of the handle flange for positioning the launching device to govern the type of movement to be imparted to the launched airplane.

6. In a missile-launching toy, a handle, a shaft journaled therein, a two-armed member fixedly associated with one end of the shaft, a pair of connectors, one end of each connector extending from each arm of said member, a peripherally grooved, ring-shaped, missile-engaging hook, the free ends of the connectors secured to the ends of said hook so that the connectors are movably guided in said groove, a missile releasably suspended from said hook, a manually operable element operatively supported in said handle for arresting the movement of said member when brought into the latter's path of rotation, thereby causing said connectors to rotate the hook to a missile-releasing position.

7. In a missile-launching toy, a rotor, a journal for the rotor, a stop member for the rotor operatively supported by said journal and being adapted to be moved into the operating path of the rotor, a missile-engaging and missile-releasing element, a pair of flexible, spaced connectors extending between the rotor and said element, the latter forming a ring-shaped hook having a peripheral groove for guiding said connectors, a

10 missile suspended by said hook, said stop member, when moved into the operating path of the rotor, causing the latter to momentarily stop, thereby changing the position of said connectors in respect to said hook so that the latter bodily revolves to its missile-releasing position.

15 8. In a missile-launching toy, a rotor, a journal for the rotor, a stop member for the rotor operatively supported by said journal and being adapted for projection into the operating path of the rotor, a missile-engaging and missile-releasing element operatively suspended therefrom, a missile suspended from said element, said element comprising a substantially ring-shaped hook having a groove at its outer periphery; a

20 25 pair of spaced, flexible connectors extending from said rotor to the ends of said hook and engaging and being guided in said groove, said connectors being caused to bodily revolve said hook in the plane passing through said groove to a missile-releasing position as their position is changed by a momentary stopping of the rotation of the rotor, when said stop member is placed into the operating path of the rotor.

25 30 35 9. In a device of the class indicated, a launcher comprising a handle, a rotor operative in the handle and including a shaft and a revolvable bar, a pair of spaced connectors secured to said bar so that one of the ends of each connector extends from a respective bar end, a hook-shaped

40 45 missile-engaging element, the other ends of said connectors being operatively associated with the ends of said element, a stop plunger operative in the handle, the rotor having means engageable by said stop plunger for arresting the movement of the rotor, thereby causing said element to be rotated and thus to be shifted by said connectors from its missile-engaging to a missile-releasing position, and a missile suspended from said element.
